UNITED STATES PATENT OFFICE.

EDWARD SMITH, OF HUNTINGTON, INDIANA.

GARBAGE-INCINERATING FURNACE.

1,037,676.

Specification of Letters Patent. Patented Sept. 3, 1912.

Application filed April 23, 1912. Serial No. 692,647.

To all whom it may concern:

Be it known that I, EDWARD SMITH, a citizen of the United States, residing at Huntington, in the county of Huntington and 5 State of Indiana, have invented new and useful Improvements in Garbage-Incinerating Furnaces, of which the following is a specification.

My invention relates to incinerating furnaces for burning ordinary refuse and garbage, and consists in certain improved features of construction, which will now be described in connection with the accompanying drawing in which,

15 Figure 1 is a vertical section, taken approximately on line A—A of Fig. 2, and a partial elevation of a furnace constructed according to my invention, and Fig. 2 is a horizontal plan section of the same.

20 In my experience with incinerating furnaces as heretofore constructed, particularly with those built according to Patent No. 971,548, to McGuire, I have found that they have to be practically rebuilt every time 25 they are allowed to cool down. To avoid this objection, I have devised the construction shown, which permits of expansion and contraction of the walls without injury.

My improved furnace consists of a hemispherical outer shell 1 of common brick, and a hemispherical inner shell or lining 2 of fire brick, the outer radius of the latter being less than the inner radius of the former, whereby an air space 3 is left between the outer shell and lining, permitting the latter to expand under the heat of the furnace when in operation, and to contract when the furnace is shut down, without injury to itself or to the outer shell which, of course, is likewise free to expand and contract by itself under such temperature variations as it is subjected to. The floor or hearth 4 of the furnace is also of fire-brick and is slightly dished toward the central 45 opening 5, from beneath which runs an arched or circular drain 6 to the outside of the furnace.

7 is a door through which ashes, etc., are removed.

8 is the outlet from the hearth to the chimney 9.

10 is a branch flue or drain, communicating at one end with the chimney and at the other with the drain 6 beneath the opening 5.

11 represents the arched fire-box, containing the grate 12, and 13 is a baffle wall to properly direct the flame from the grate over the material to be burned.

14 is the hopper through which the material is introduced, falling, of course, onto 60 the floor or hearth over the opening 5.

The furnace being already in operation, the moisture is at once dried out and then the material is burned. The ashes and incombustible refuse are withdrawn through 65 door 7, while some liquid and fine ash may pass out through drains 6 and 10.

Having thus described my invention, what I claim is:—

An incinerating furnace consisting of an 70 outer hemispherical shell having a horizontal base, an inner hemispherical lining spaced from said shell, a chimney connected to the shell and base, a hearth on said base having a central opening which communicates with an opening in the base, said chimney adjacent its base being formed with a downwardly inclined outlet that extends through the said lining and has the wall formed by its bottom extending adjacent the 80 hearth, said base being formed with an arched drain which at one end communicates with said base opening and at its opposite end extends through the periphery of the base, a branch drain formed in the 85 base that extends from the base opening and is curved upwardly to extend into the outlet at the end thereof adjacent the hearth, and a fire box at one side of the hearth.

In testimony whereof I have hereunto set 90 my hand in presence of two subscribing witnesses.

EDWARD SMITH.
